UNITED STATES PATENT OFFICE.

ALVAH JEWEL HOWD, OF NAMPA, IDAHO.

MILLING-MACHINE.

1,284,344.

Specification of Letters Patent. Patented Nov. 12, 1918.

Application filed May 29, 1917. Serial No. 171,673.

To all whom it may concern:

Be it known that I, ALVAH JEWEL Howd, a citizen of the United States, residing at Nampa, in the county of Canyon and State 5 of Idaho, have invented certain new and useful Improvements in Milling-Machines, of which the following is a specification.

This invention relates to improvements in milling machines and more particularly 10 to machines adapted to operate upon castings of irregular shapes.

One of the objects of the present invention is to provide a milling machine of the above character particularly adapted for 15 use on castings forming parts of the improved rotary gas engine illustrated and described in my patent dated June 5th, 1917, 1,229,179. A further object is to provide a milling machine of the above character 20 which will be reliable, efficient and largely automatic in use and operation and having relatively few parts which will be inexpensive to manufacture.

Other objects will be in part obvious from 25 the annexed drawings and in part indicated in connection therewith by the following analysis of this invention.

This invention accordingly consists in the features of construction, combination of 30 parts and in the unique relations of the members and in the relative proportioning and disposition thereof, all as more completely outlined herein.

To enable others skilled in the art so fully 35 to comprehend the underlying features thereof that they may embody the same by the numerous modifications in structure and relation contemplated by this invention, drawings depicting a preferred form have 40 been annexed as a part of this disclosure, and in such drawings like characters of reference denote corresponding parts throughout all the views, in which—

Figure 1 is an elevational view showing 45 such parts of the complete machine as are necessary to understand the invention;

Fig. 2 is a section on line 1—1 of Fig. 1.

Fig. 3 is a sectional view of the work, the section being taken longitudinally of one 50 of the grooves 6 on line 3—3, Fig. 2, and showing a cutter operating in the groove.

The present invention is particularly adapted for use upon side wall castings of the rotary gas engine shown in my above- 55 referred to patent, which castings have a

relatively flat surface containing a series of cylinders formed by concaved depressions gradually increasing in depth toward their center and of such curvature as to receive piston heads of a rotary piston member carried by a rotor revolving between two such plates. This casting is indicated at 5 in Fig. 1 and the openings or cylinders at 6. Each groove 6, at its ends is relatively wide, but shallow, while at its middle it is relatively deeper, and undercut so as to leave overhanging portion 6^a, defining a relatively narrow throat or gullet. These grooves extend, as will be seen from Fig. 1, in directions tangential to a circle concentric to the axial center of the work.

The milling machine comprises a suitable base 7 having a work-holder 8 to which the casting is adapted to be secured. The work-holder is provided with a circumferential 75 rack 10 engaging a worm 11 mounted upon a shaft 12 in the bed of the machine whereby the casting is rotated at a predetermined rate of speed as will be hereinafter more fully explained.

A cutter head 13 is supported by an upright 80 14 on an auxiliary bed 15 which may be moved longitudinally of the machine by means of a rack 16 on its under side co-acting with a pinion adapted to be turned by a 85 hand wheel 17 for the purpose of positioning the cutter-head with respect to the casting.

A source of power indicated by belt 18 is connected with pulleys 20 and drives a main 90 shaft 21 for turning the cutters. A second shaft 22 is mounted parallel to the shaft 21 and both shafts are provided with a series of speed-reducing gears 23 for the purpose of driving a gear 24 mounted upon a sleeve 95 shaft 25 at greatly reduced speed. This sleeve shaft 25 extends through the upright 14 and is adapted to rotate the cutter head 13 at the desired rate of speed. A second pinion 26 meshes with a pinion 27 upon the 100 shaft 22 for the purpose of driving the worm and gear mechanism for rotating the work-holder 8.

In Fig. 2 it will be seen that the shaft 21 is provided with a bevel gear 28 at its end 105 meshing with four bevel gears 30 positioned thereabout for driving each one of the individual cutters 31. These cutters are substantially spherical in shape except for their connecting shanks 32 and the surface is pro- 110

vided with longitudinal cutting edges as indicated. The individual cutters are detachably mounted in any desired manner upon shafts 35 upon which the pinions 30 are 5 mounted.

It will thus be seen that the individual cutters are rotated at relatively high speed by the shaft 21 and the entire cutter head 13 is rotated at a reduced speed about the shaft 10 21 by means of the sleeve shaft 25.

It will be seen from Fig. 1 that the cutting head rotates in a plane at right angles to the face of the work, and that this plane of rotation does not intersect the axis of the 15 work, but is to one side of the axis, and that the path of the cutters is entirely above a horizontal plane extending through said axis. Now assuming that the cutter head is rotating in a clockwise direction, then as the 20 forward end of the cutter approaches the work it will enter the forward end of cylinder or groove, and rotate therein. While the cutter is moving toward and into the work and downward the work is moving 25 downward in direction of the arrow, so that the groove 6 is moving downwardly and longitudinally, with respect to the cutter.

As seen in Fig. 2, each cutter is spherical in shape and has a hub 31^a which is peripherally toothed. Therefore as the cutter moves into the work, the spherical cutter passes down between the lips 6^a, as shown in Fig. 2, the hub milling the side walls of the lips and the body cutting or milling that 35 portion of the groove inward of the lips.

While the milling machine is particularly designed to mill cavities of the peculiar form illustrated, yet it will be obvious that tangential cavities, elliptical, or of other cross- 40 sectional form may be cut, or milled on this machine, by disposing the axis of the cutters farther from the face of the work, or changing the shape of the cutters.

By referring to the patent above mentioned it will be seen that the piston heads correspond to the cutters 31 herein shown and rotate in a plane at right angles to the surface of the casting 5 at any desired ratio of speed, preferably 1 to 4. That is, each 45 piston head successively engages every fourth cylinder. Accordingly the work-holder is rotated at a speed proportional to the rotation of the cutter head whereby each cutter 31 gradually moves into engagement 55 with its respective cylinder at one end and passes out the opposite end as the rotative movement of the casting 5 takes place.

The casting is furnished with these cylinders cast therein, but of course in a very 60 roughened condition, and after the surface has been planed it is placed upon the milling machine and all but one of the cutter-heads 31 removed. After the first cutter tool passes through the first cylinder the other cutters 65 are then applied and the machine started,

whereby the cutters automatically feed into and out of the successive cylinders as the casting and cutter heads are revolved.

It is thus seen that the present invention comprises a simple and practical milling machine adapted to accomplish among others all of the objects and advantages herein set forth. 70

As many changes could be made in the above construction and many apparently widely different embodiments of my invention could be made, without departing from the scope of the appended claims, it is intended that all matter contained in the above description or shown in the accompanying drawings shall be interpreted as illustrative and not in a limiting sense. 75

In the claims appended the terms "rotative" and "rotatable" are used to define the movement of a body around an axis passing through the body, while "revoluble" is used to define the movement of a body which rotates around an axis exterior to itself. 80

Having thus described my invention what I claim as new and desire to secure by Letters Patent is: 90

1. A machine of the character described including a rotatable work holder, a cutter bodily movable in a plane at right angles to the plane of the work holder and rotatable on its own axis and means for simultaneously moving the cutter bodily, rotating the cutter on its own axis, and rotating the work holder. 95

2. A machine of the character described, including a rotatable work holder, and a cutter revoluble around an axis in a plane at right angles to the plane of the work holder, and rotatable on its own axis in a plane parallel to the first named axis. 100

3. A machine of the character described, including a rotatable work holder, and a cutter revoluble around an axis in a plane at right angles to the plane of the work holder, and rotatable on its own axis in a plane parallel to the first named axis, the first named axis extending tangentially to a circle concentric to the axis of rotation of the work holder. 105

4. A machine of the character described, including a rotatable work holder, and a cutter revoluble around an axis in a plane at right angles to the plane of the work holder, and rotatable on its own axis in a plane parallel to the first named axis, the first named axis extending tangentially to a circle concentric to the axis of rotation of the work holder and the plane of revolution of the cutter being also tangential to a circle concentric to the axis of rotation of the work holder. 110 120

5. A machine of the character described including a rotary work holder, a cutter, a shaft on which it is mounted, means for rotating the shaft and cutter in a plane at right angles to the plane of rotation of the work 125 130

holder, and means for simultaneously rotating the work.

6. A machine of the character described including a rotary work holder, a main shaft 5 extending parallel to the work holder, a cutter carried by the shaft with its axis at an angle thereto, the cutter being revoluble bodily around the main shaft and being also rotatable on its own axis, and means for revolving the cutter bodily around and in a plane at right angles to the main shaft, and to the plane of rotation of the work, and means for simultaneously rotating the work in the same general direction as the bodily 10 movement of the cutter when it is in contact with the work.

7. A machine of the character described including a rotary work holder, a main shaft extending parallel to the work holder, a cutter 20 carried by the shaft with its axis at an angle thereto, the cutter being revoluble bodily around the main shaft and being also rotatable on its own axis, and means for revolving the cutter bodily around and in a plane at right angles to the main shaft, and to the plane of rotation of the work, and means for simultaneously rotating the work in the same general direction as the direction 25 of revolution of the cutter when it is in contact with the work but at a speed different from the speed of revolution of the cutter around the axis of the shaft.

8. A machine of the character described including a rotatable work holder, a rotatable 35 cutter, a main shaft extending parallel to the work holder, a cutter shaft upon which the cutter is mounted and extending radially from said main shaft, independent means for rotating the main shaft and the cutter shaft, 40 and means for rotating the work at a predetermined speed and rotating the main shaft at another predetermined speed, said main shaft extending tangentially to a circle concentric to the center of motion of the work, 45 and the plane of revolution of the cutter around the main shaft being tangential to a circle concentric with the work.

9. A machine of the character described including a rotatable work holder, a main 50 shaft extending parallel to the work holder, means for rotating said main shaft, a plurality of radial cutter shafts mounted upon the main shaft and rotatable therewith in a plane at right angles to the plane of the work, means for rotating the radial shafts, 55 cutters mounted on the radial shafts for rotation therewith, the main shaft extending tangentially to a circle concentric to the axis of movement of the work and the radial shafts, and said cutters revolving around the axis of the main shaft in a plane tangential to a circle concentric to the axis of the work.

10. A machine of the character described 65 including a rotatable work holder, a main

shaft extending parallel to the work holder, means for rotating said main shaft, said main shaft being disposed in a line tangential to a circle concentric to the axis of the work holder, a plurality of radially disposed cutter shafts mounted upon the main shaft and rotatable therewith in a plane at right angles to the plane of rotation of the work holder, means for rotating the radial shafts on their own axes, cutters mounted on 70 the radial shafts for rotation therewith, the plane of bodily revolution of said cutters around the axis of the main shaft being tangential to a circle concentric to the center of motion of the work, said cutters being 75 spherical in form.

11. A machine of the character described including a rotatable work holder, a main shaft extending parallel to the work holder, means for rotating said main shaft, said 80 main shaft extending tangentially to a circle concentric to the axis of the work holder, a plurality of radially disposed cutter shafts mounted upon the main shaft and rotatable therewith in a plane at right angles to the 85 plane of rotation of the work holder, means for rotating the radial shafts on their own axes, cutters mounted on the radial shafts for rotation therewith, the plane of bodily revolution of said cutters around the axis of 90 the main shaft being tangential to a circle concentric to the center of motion of the work, said cutters being spherical in form, each of said cutters at its inner end being 95 formed with a hub having cutting teeth. 100

12. A machine of the character described including a rotatable work holder having gear teeth on its circumference, a main shaft extending parallel to the work holder, means for applying power to the main shaft, the main shaft extending tangentially to a circle concentric to the axis of rotation of the work holder, a sleeve mounted on the main shaft and having radially disposed cutters carried thereby, means driven by said main 105 shaft for rotating said sleeve to carry the cutters into and out of engagement with the work, means actuated by the main shaft for individually rotating said cutters, each around its own axis, a worm shaft engaging the teeth of the work holder, and means actuated by said main shaft for rotating said worm shaft, each of said cutters being 110 formed at its end adjacent the axis of the main shaft with a hub having cutting teeth. 115

13. In a machine of the character described, a rotatable work holder, a spherical toothed cutter having a hub provided with peripheral cutting teeth, means for rotating the work holder at a predetermined speed, means for rotating the cutter, and means for carrying the cutter against the face of the work supported in said holder, causing said cutter to move with the work for a predetermined distance, and then out of the work, 120 125 130

the path of movement of the cutter being disposed tangentially to a circle concentric to the center of motion of the work and the axis of said path of movement extending 5 tangentially to a circle concentric to the center of motion of the work, said center of motion of the cutter being disposed in such proximity to the face of the work that the cutter when its axis extends at right angles

to the face of the work will be disposed with- 10 in the face of the work with its hub intersecting said work.

In testimony whereof I affix my signature in presence of two witnesses.

ALVAH JEWEL HOWD.
